UNITED STATES PATENT OFFICE.

GEORGE LANE, OF FORT LEE, NEW JERSEY.

PROCESS OF PRODUCING LEGENDS IN BLACK ON MOTION-PICTURE NEGATIVES.

1,300,178.

Specification of Letters Patent.

Patented Apr. 8, 1919.

No Drawing.

Application filed November 13, 1918. Serial No. 262,374.

To all whom it may concern:

Be it known that I, GEORGE LANE, a subject of the King of England, and a resident of Fort Lee, in the county of Bergen and State of New Jersey, have invented a new and Improved Process of Producing Legends in Black on Motion-Picture Negatives, of which the following is a full, clear, and exact description.

10 This invention relates to motion picture photography, and has particular reference to the process of producing legends, titles, inscriptions, or the like, on motion picture films in a manner that is most expeditious, 15 and hence rapid and cheap and which moreover is capable of the best possible illustrative results.

In the usual or old practices there are three processes involved in making of negative films: first, by hand lettering or inscribing on a black card; second, by printing on a black card with aluminum ink, or using a viscous ink or some other gelatinous substance and powdering the same with aluminum powder, or its equivalent. These two processes are the most commonly used to make a negative for production purposes, but the first is expensive and slow, while the second is uncertain and consequently unsatisfactory. Furthermore in both of these methods the card itself because of its color character is apt to photograph and produce a grayish effect on the final projection upon the screen. The third old process is to print 30 on a white card and photograph the same in a motion picture camera whereby there is produced what is technically termed a positive film, from which to obtain a negative it is run through a motion picture printing machine to make what is called a "negative dupe" or "duded negative."

The first method mentioned is most universally used by high class producers for thereby it is almost certain to produce a good quality of title or legend on the screen. The second and third methods are not used by the highest class producers owing to the faults and difficulties accompanying them. While it is not impossible to make a fairly good "negative dupe" it is nevertheless essential for such production that the machine making it must possess a fine degree of accuracy to give a perfect contact and definition. Only in plants that are large enough 55 to employ first class mechanics who are skilful and reliable enough for the output

to be depended upon can this process be employed and even then either a special machine is used or else the standard machine must be changed in some essential parts to insure that perfect definition.

In the practice of my invention I employ or resort to a succession of steps all of which considered severally are more or less familiar in other relations to photographers or motion picture artisans, but which when associated in a complete process I believe involve a new and meritorious process because the results obtained by the same are much more satisfactory to the theater going public and at the same time the work can be produced much more rapidly, easily and cheaply than in the practice of any motion picture process or development heretofore known or practised.

75 In the first step in my process I employ a sheet of pure white thin or diaphanous paper, and hence having a uniform clear texture of any convenient size. On this sheet of white paper I print, paint, draw, or otherwise produce or place the legend, title, figure, or other device to be reproduced and projected, using for this purpose printers' type and black ink or any other suitable means whereby a black or dark color is 80 printed or placed upon the sheet, such color being necessarily substantially opaque as distinguished from the paper constituting the sheet on which the legend or device is printed or placed. From what has been 85 stated it is to be understood that my process relates particularly to the preparation of what is commonly termed in the art the title and which consists of descriptive matter or the like employed as a preface to the 90 regular motion picture. I wish it to be understood, however, that the practice of my improved process is susceptible of a much wider field than that just indicated.

95 The result of the first step of my process 100 may be understood therefore as having the visible characteristics of a sheet of paper printed in positive characters similar to the ordinary page of a book. Consequently if the work is such as to involve a decorative 105 device that must be produced by the hand of an artist or the like the production thereof obviously is much simplified by the positive character of the picture or other device.

110 During the second step of my process I subject the white sheet above described to

the actinic effect of a sharp light in close contact with the sheet of photographic print paper of such a character that the actinic rays of light acting through the white sheet at every point except where obscured by the printing or other device applied thereto by dark ink or paint, will become when developed absolutely black, while those portions covered by the dark legends carried by the initial white sheet in close or direct contact with the photo print paper will be absolutely white. At the end of the proper time of exposure of the photo print as above set forth, said photo print is developed in accordance with any well understood practice of photo development and the result therefore at the end of this second step of my process is or may be described as being a photo print sheet having thereon perfectly white letters or other characters and having a surrounding field or background that is black. At this point it is to be observed that since the initial sheet having the clearly outlined or clear cut characters applied thereto in black or dark color is during the second step of the process held firmly by the printing machine or the like in close contact with the photo sheet, the outline of the white characters produced or developed on the photo sheet by this second step of the process must be very clear and have sharp outlines. The photo sheet just referred to as the result of the second step having the characters in white on a dark background may be described as being negative as to color, but as to the legible nature of the letters or characters they may be either positive or negative depending upon the direction of the light through the initial white sheet at the time the print is made.

The third step in my process is to support the aforesaid negative or photo sheet in flat position and photograph it by means of any usual motion picture camera. The negative film when so photographed and developed is a film similar in color arrangement to the initial sheet, having absolutely black clear cut sharply outlined letters or characters constituting the legend or other device and having a perfectly clear or white background. The words or other devices so formed upon the white film may be either positive or negative as to legible character, but in either event the film so produced constitutes what may be termed a permanent negative film from which any number of reproductions may be made the same as reproductions are ordinarily made from the animated picture negative. Thus it will be seen that in the practice of my invention I obtain both negative and positive film each perfect of its kind for commercial use with none of the delays and disadvantages already enumerated.

65 As a sub-step in my process when the

title, legend, or inscription is printed upon the original sheet or card, I prefer to form first a printed impression upon a heavy card and then place the thin white or diaphanous sheet directly upon the printed card while the ink is yet moist, and then printing another impression on the face of the sheet so placed. Thereby I get not only the direct impression upon the face of the sheet, but also an offset impression from the first print with the result that the thin or diaphanous sheet will have the printed impression on both faces insuring that no matter which face of the sheet is applied to the photo print sheet in the second step of the process, a direct contact between the printed legend and the photo print sheet will be assured. It is, of course, important that the ink used shall be uniformly distributed so as to produce a solid color or one that is completely opaque. I have found, therefore, that a more even distribution of the ink on the paper than is usually found in printing purposes is insured if a small bit of the following mixture be added: cottonseed oil five parts and oil of citronella one part.

I claim:

1. In motion picture photography, the herein described process of producing legends in black on a negative film comprising the following steps: (1) forming the legend in positive characters in dark or a thin white sheet; (2) making a photo print of the legend so produced in close contact with the photo print sheet and developing the same producing the legend with negative colors, and (3) photographing said negative photo sheet on a motion picture film and developing the same producing thereon black characters on a white background, and constituting thereby a permanent negative film.

2. In motion picture photography, the herein described process of producing a permanent negative film comprising the following steps: (1) forming the legend, title, or other device in opaque characters on a diaphanous sheet; (2) making a photo print through said sheet and in direct contact therewith and developing the print producing white characters for the legend, title, or other device and with a solid black background, and (3) photographing said photo print on a motion picture film and developing the same producing thereby and thereon black characters on a white or clear background, said film being used permanently for multiple reproduction.

3. In motion picture photography, the process of producing a permanent negative film comprising the following steps: (1) printing with a dark or opaque ink on a heavy sheet or card the legend to be produced; (2) placing over the printed impression while yet moist a thin white or diaphanous sheet and making another

printed impression upon the face thereof causing an offset impression to be made on the back of the sheet from the first printed impression; (3) making a photo print through said thin sheet with the printed impression in direct contact with the print sheet and developing the print producing white characters for the legend, and (4) photographing said photo print on a motion picture film and developing the same producing thereby and thereon solid black clear cut characters on a white or clear background.

GEORGE LANE.
